UNITED STATES PATENT OFFICE

EMERY J. WILSON, OF CLEVELAND, OHIO, ASSIGNOR TO THE THEW SHOVEL COMPANY, OF LORAIN, OHIO, A CORPORATION OF OHIO

BACK-DIGGING EXCAVATOR

Application filed April 21, 1927. Serial No. 185,569.

This invention relates to excavating machines and more particularly to back digging ditchers in which the scoop or dipper is moved toward the truck or machine base during the filling or digging movement. Such machines, when provided with a rigid dipper incapable of being tilted or turned on the dipper stick, do not maintain uniform or desirable angle or rake of the dipper teeth by accommodating them to the varying slope of the surface being excavated and, moreover, usually require closure controlled dippers with accompanying provision for closure operation, and when provided with a tilting dipper can not carry the load outwardly to a point beyond the boom end and there dump it in a restricted area, but at best have scattered the load during outward swing.

My invention has for its object to provide an improved excavator of this type including a tilting dipper requiring no closure, but provided with the necessary control devices by which its position may be accommodated to the varying slope and the most efficient angle or rake thereby maintained, and which also may be carried out and dumped in a restricted area remote from the central axis and beyond the boom end.

A further object is to provide an improved tilting dipper for connection to a dipper stick, with a special arrangement of the dipper as regards its mounting on the stick and its balance or lack of balance around its pivot, as well as latching or other devices enabling motion of the dipper upon the stick to be secured or regulated by simple control devices and particularly by the normal control devices on such excavators, such as the drag line, hoisting line and crowding engine.

Further objects of the invention are in part obvious and in part will appear more in detail hereinafter.

In the drawings which represent one suitable embodiment of the invention Fig. 1 is a side elevation showing the dipper filled and ready to be moved out to dumping position; Fig. 2 is a detail view correspond-

ing to Fig. 1 and showing the dipper in dumping position; Fig. 3 is a side elevation on a larger scale of the dipper and its control devices; Fig. 4 is an elevation from the left in Fig. 3, parts being broken away; and Fig. 5 is a diagrammatic view illustrating the operation of the excavator in digging a ditch.

The invention may be applied to any excavator including a swinging boom and a dipper stick movable or adjustably mounted thereon and to which my tilting dipper is connected. It is shown applied to a portable excavator including a truck mounted upon a base 2 of the track laying tractor type upon which is a turn table supporting the body 4 on which is carried the excavating mechanism including, among other things, the usual shaft 5 carrying drums for operation of the drag line 6 and hoisting line 7 and a drum 8 for actuating the cable 9 for raising the boom. Said drums are geared and are driven in the customary manner and are provided with the usual brake devices (not shown) for control by the operator.

At one end of the body is mounted the boom 10 turning upon the horizontal pivot 11 and capable of lateral swinging movement by rotation of the turn table. At a point intermediate of the boom ends provision is made for mounting a dipper stick 12 actuated by any suitable crowding engine. In the form shown the dipper stick is provided with rack teeth 12^a engaged by a pinion 13^a on a shaft 13 provided with a sprocket wheel coupled by the chain 14 to a sprocket on shaft 11 from which a second chain 15 leads to the shaft 16 actuated by any suitable crowding engine. The dipper stick is mounted, as is usual, for rotation or swinging movement in a vertical plane around the shaft 13 and for longitudinal sliding motion in its mounting by actuation of the crowding engine. The hoisting line 7 passes from its winding drum over a sheave 10^a on the end of the boom and thence directly to the dipper stick, or, as shown, a loop of the line may pass over a sheave 17 connected to the dipper stick, the two 100

ends of the loop passing over two pulleys 10^a and one end of the line being dead ended, as at 7^a. The drag line may likewise be suitably dead ended, as on the boom, and a pass over sheaves 18 on the boom and a sheave 19 connected to a yoke 20 pivoted to the side walls of the bucket or dipper 22 at the pins 21, which extend laterally for a purpose which will later appear.

The bucket or dipper, shown in detail in Figs. 3 and 4, is of scoop form. In other words it has no closure but is filled by the excavating movement and is dumped by tilting or turning it so that the load comes out through its only opening. It includes a scoop shaped body portion 23 provided with an open mouth, along one edge of which—the digging edge—are the usual teeth 24, the body being mounted to swing on trunnions 25 between the hook shaped arms of a yoke 26 rigidly attached to the dipper stick.

The axis of swinging movement of the dipper on the dipper stick at the trunnions 25 is considerably off center with reference to the center of gravity of the bucket either empty or loaded, the center of gravity being located at different points within approximately the restricted area A, Fig. 3, according to whether the dipper is empty or partially or wholly loaded. Therefore, under practically all conditions and excepting only as noted hereafter, the dipper tends to swing by gravity toward a position in which it 35 maintains or holds its load, the limit of such movement being the engagement of the extensions of pins 21 in the curved seat portions of the hook shaped arms of yoke 26, or in the position shown in Fig. 1. Motion 40 of the dipper in the opposite direction—the clockwise direction Fig. 1,—for dumping, is secured by the outward push of the crowding stick or by a pull on the drag line or both.

For proper control of the dipper it is provided with latch means actuated automatically by the usual dipper control devices and therefore not requiring any special actuating line or device. The latching means shown 50 includes a pawl 27 pivoted at 28 to a pin or shaft mounted in the yoke, said pawl having a tooth portion 29 beyond which is an extension or tongue 30. Adjacent the tooth 29 and pivoted at 31^a on opposite sides of the pawl are two generally elliptical cam members 31. The tooth 29 of the pawl cooperates with a series, four being shown, of ratchet teeth 32 formed as part of a single member and lying between parallel guide 55 ways or flanges 33 thereof, and beyond said member the scoop carries a fixed stop shoulder or abutment 34.

In the dumped position of the dipper, shown in Fig. 2, the tooth 29 engages the 60 fixed stop or abutment 34, thereby limiting

any motion of the dipper in the dumping direction. In the filled position or when the bucket is being moved after filling to dumping position the parts occupy the position shown in Fig. 1, with the cams 31 and the tooth 29 lying beyond or to the right, Fig. 1, of the ways 33 and ratchet teeth 32, but the tongue or extension 30 is still in engagement with the bucket wall and lying upon the ways 33. If the bucket is now moved toward dumping position the cams 31 meet the curved ends 33^a of the ways 33 and swing back on their pivots 31^a until their rear shoulders 35 meet the fixed abutments 35^a on the pawl 27, said cams thereupon riding up upon the edges of the ways 33 and lifting the tooth 29 above the level of the ratchet teeth 32, enabling the bucket to be turned freely in the clockwise direction Fig. 1 until finally the cams ride down over the far ends of the ways 33 and enable the tooth 29 to engage the stop abutment 34. If the bucket is now moved in the counterclockwise direction, Fig. 1, the cams 31 meet the far ends of the tracks 33 and swing away from their abutments 35, permitting the tooth 29 of the pawl to drop and ride in turn over the several ratchet teeth and engage therewith and prevent return motion of the bucket in the dumping direction until the cams have been completely traversed over their respective ways 33 to the position shown in Fig. 1 and then returned as before described. The purpose of this arrangement and the reasons for operation of the parts as described will appear hereafter.

Referring now to Fig. 5, which illustrates a full sequence of operation of the excavator, let it be assumed that the cycle of operations begins with the bucket in the position shown in full lines at position A, to wit, the dumped position, it being understood of course that the turn table may be swung around 90°, more or less, from the plane of digging motion to dump the load out at one side of the ditch being excavated, which extends in the direction of travel of the excavator. In this dumping position A it will be observed that the crowding stick has been pushed out to its limit and is hoisted nearly to parallelism with the boom. The bucket has been dumped by a pull of the drag line. Its center of gravity is inwardly of its axis of swing and it tends to remain in the dumping position and to be held there by the engagement of pawl 27 against the limit stop 34. By proper actuation of the drag and hoisting lines the dipper stick is moved downwardly to position B, with the bucket teeth forced into the ground. This occurs only in starting a ditch or in the first opening of the ground and the operation when full depth is reached will be explained more fully hereafter. Upon reaching position B, the crowding stick is pushed outwardly, 130

using the teeth of the bucket as a fulcrum against the ground, the motion of the crowding stick causing the bucket to turn as the digging proceeds until finally its center of gravity is outwardly of its center of tilt on the dipper stick whereupon the gravity effect of the bucket moves it more and more toward the final filled position. The bucket sweeps are extended more and more until finally the bottom of the ditch is reached. Now, after each dumping operation the bucket is brought down to position C in which gravity turns it to a position with its flat bottom or wall parallel with the ditch bottom. It is advanced into the earth and is caused to move up the slope successively through positions D and E. During this movement the drag line and crowding engine are relatively manipulated not only to advance the bucket along its path of cut but to also permit gravity to progressively change the bucket position by progressive tilt upon the dipper stick so that the angle or rake of the teeth is maintained uniform with respect to the slope of the surface being excavated. As the cut proceeds the excavated material falls into the bucket and more and more assists in turning it to maintain uniform angle or rake. When position E is reached and the cut is completed the drag line is slackened off to permit the bucket to settle fully to load maintaining position with its pin extensions 21 settled in the crotches of the hook shaped yoke arms 26 and the bucket is moved through a series of positions F outwardly to the position shown in dotted lines at A. During such outward motion or after it is completed the boom may be swung laterally to the side of the ditch and throughout the movement the position of the bucket is such as to maintain the load and not permit it to spill. When dotted position A is reached the crowding stick is held and the drag line is drawn in or the drag line is held and the stick is crowded out to tilt and overbalance the bucket and permit its load to drop within a restricted area directly beneath it, either into a truck or upon a pile on the ground, and obviously the dumping position may be practically anywhere within the range of the bucket and not necessarily at the farthest point from the center.

This invention, among others, has two distinct advantages. In digging a narrow ditch it is possible to carry each load outwardly laterally to a point considerably beyond the edge of the ditch and there dump it, so that it is unnecessary as in prior constructions to either dump the load close to the edge of the ditch or to scatter it over the ground as the bucket is moved outwardly. Liability of crushing in the walls of the ditch by the weight of material deposited upon them is therefore obviated. Also, in

excavating up along the slope through positions C, D and E, the angle of rake is varied to meet the variation in slope and the teeth of the bucket are always presented at the most efficient cutting angle and are not dragged across the slope while standing out vertically or perpendicularly thereto. 70

What I claim is:

1. An excavator provided with a swinging boom, a dipper stick mounted thereon, a dipper mounted to swing on said stick and balanced to normally tend when loaded to swing toward a load maintaining position, a drag line operatively connected to said dipper in a position to dump said dipper when loaded, and holding means between said stick and said dipper for resisting the drag line pull to maintain the dipper in a plurality of digging positions on the dipper stick. 75
2. An excavator provided with a swinging boom, a dipper stick mounted thereon, a dipper mounted to swing on said stick and balanced to normally tend when loaded to swing toward a load maintaining position, a drag line operatively connected to said dipper, and self acting holding means for resisting the drag line pull to maintain the dipper in a plurality of digging positions on the dipper stick. 80
3. An excavator provided with a swinging boom, a dipper stick mounted thereon, a dipper mounted to swing on said stick and balanced to normally tend when loaded to swing toward a load maintaining position, a drag line operatively connected to said dipper, self acting holding means for resisting the drag line pull to maintain the dipper in a plurality of digging positions on the dipper stick, and means for overcoming the effect of said holding means for dumping said dipper. 85
4. An excavator as in claim 2 wherein the holding means is in the form of ratchet and pawl mechanism arranged between the dipper stick and the scoop. 100
5. An excavator as in claim 2 wherein the holding means is in the form of ratchet and pawl mechanism arranged between the dipper stick and the scoop and comprising a pawl carried by the dipper stick, and a plurality of teeth carried by the scoop and adapted to engage the pawl. 115
6. An excavator as in claim 2 wherein the holding means is in the form of ratchet and pawl mechanism arranged between the dipper stick and the scoop and comprising a pawl carried by the dipper stick, a plurality of teeth carried by the scoop and adapted to engage the pawl, and means for raising said pawl out of the range of said teeth and effective when the dipper is thrown to extreme load maintaining position. 120
7. An excavator as in claim 2 wherein the 130

holding means is in the form of ratchet and pawl mechanism arranged between the dipper stick and the scoop and comprising a pawl carried by the dipper stick, a plurality of teeth carried by the scoop and adapted to engage the pawl, means for raising said pawl out of the range of said teeth and effective when the dipper is thrown to extreme load maintaining position and comprising a cam member carried by the pawl and the cooperating rail carried by the dipper.

8. In an excavator, a swinging boom, a dipper stick mounted thereon and movable to a position in which it extends outwardly beyond the boom end, a dipper pivoted to said stick with its pivotal point toward the front and near the bottom of said dipper whereby it may swing toward load maintaining position when loaded and toward extreme dumping position when its center of gravity is swung forward of said pivot, a drag line connected to said dipper above the pivot and tending throughout its various positions to swing it to dumping position, and holding means for resisting the drag line pull to maintain the dipper in a plurality of digging positions on said stick.

9. In an excavator, a swinging boom, a dipper stick mounted thereon and movable to a position in which it extends outwardly beyond the boom end, a dipper pivoted to said stick with its pivotal point toward the front and near the bottom of said dipper whereby it may swing toward load maintaining position when loaded and toward extreme dumping position when its center of gravity is swung forward of said pivot, a drag line connected to said dipper above the pivot and tending throughout its various positions to swing it to dumping position, and holding means for resisting the drag line pull to maintain the dipper in a plurality of digging positions on said stick and comprising ratchet and pawl mechanism arranged between the stick and dipper.

10. In an excavator, a swinging boom, a dipper stick mounted thereon and movable to a position in which it extends outwardly beyond the boom end, a dipper pivoted to said stick with its pivotal point toward the front and near the bottom of said dipper whereby it may swing toward load maintaining position when loaded and toward extreme dumping position when its center of gravity is swung forward of said pivot, a drag line connected to said dipper above the pivot and tending throughout its various positions to swing it to dumping position, holding means for resisting the drag line pull to maintain the dipper in a plurality of digging positions on said stick and comprising ratchet and pawl mechanism arranged between the stick and dipper, and stop means arranged between the stick and

dipper for limiting the final dumping position of the latter.

In testimony whereof I hereby affix my signature.

EMERY J. WILSON.
